UNITED STATES PATENT OFFICE.

FRANK H. MARTIN, OF CARTERVILLE, ILLINOIS.

AUTOMATIC RAILROAD-SWITCH THROW AND LOCK.

1,423,351.

Specification of Letters Patent. Patented July 18, 1922.

Application filed July 9, 1921. Serial No. 483,544.

To all whom it may concern:

Be it known that I, FRANK H. MARTIN, a citizen of the United States, residing at Carterville, in the county of Williamson 5 and State of Illinois, have invented a new and useful Automatic Railroad-Switch Throw and Lock, of which the following is a specification.

This invention has reference to automatic railroad switch throws and locks, and its object is to provide a device of such character wherein there are no springs which could be so strained as to cause a break, wherein ties may be replaced and the track surfaced and lined up without any obstruction to the fixtures of the throwing device, whereby liability of breakage is reduced to a minimum, and where many disadvantages of other switching installations are avoided.

The invention contemplates the use of devices known as tripvees capable of operation from either side of a railway vehicle or engine, and which tends to hold the vehicle to the track rather than derail it. Moreover, the invention permits a train or vehicle to throw a switch for a siding and then close the switch after passing through, or the reverse, without a stop and as fast as the train will keep the track.

The invention will be best understood from a consideration of the following detailed description, taken in connection with the accompanying drawing forming part of this specification, with the understanding, however, that the invention is not confined to any exact conformity with the showing of the drawing, but may be changed and modified, so long as such changes and modifications mark no material departure from the salient features of the invention, as expressed in the appended claims.

In the drawing:

Fig. 1 is a plan view, more or less in diagram, of a switch-operating installation.

Fig. 2 is a side elevation thereof.

Fig. 3 is a view, partly in plan and partly in horizontal section, of the switch mechanism.

Fig. 4 is a side elevation, partly in section, of the structure of Fig. 3.

Fig. 5 is an elevation of one of the tripvees.

Fig. 6 is a view of the structure of Fig. 5, taken at right angles to Fig. 5.

Fig. 7 is a plan view of the structure of Fig. 5.

Figs. 8, 9 and 10 are detail views of connecting means employed in the switch mechanism.

Fig. 11 is a more or less diagrammatic elevation of a motor vehicle capable of operating the switch system.

Fig. 12 is a plan view thereof.

Fig. 13 is a cross section of a portion of the motor car showing means for operating the tripvees.

Referring to the drawings, and more particularly to Figs. 1 to 10, there is shown a railroad track comprising a main line A and a branch line or siding B connected by a switch C. The switch comprises points 1 of usual construction, a switch stand 2 connected by a cross-bar 3 to the points 1 and enclosed by a box 4 for protection. The switch stand includes a rocker arm 5 connected to rods or cables 6, so that the switch points may be thrown from side to side in setting the main track A for straight-through passage or coupling up the siding B to the main track A, as may be desired.

The stand 2, rocker arm 5 and cross bar 3, may follow the practice in ordinary switch stands and requires no special description.

Arranged at the side or sides of the track, out of the way of the ties and of an engine or a train traveling along the track, are foundation blocks 7 each carrying a plate 8 provided with journal bearings 9 traversed by a rock shaft 10, fast to which at opposite ends thereof are rocker arms 11 terminating in 90 eyes 12 or other appropriate means for attaching the rods 6 or other like devices in the form of rods, cables or strands.

At one end of each shaft 10, there is secured a plate 13 which may be of expanding 95 conformation as it rises from the shaft, and at the upper end, it carries, in spaced relation, two fingers 14 pivoted to the plate 13 and held in the spaced relation by springs 15 so as to constitute V-shaped entering channels for operating devices to be described, the channels and parts defining them forming what I term tripvees.

In order to simplify the description, the strands 6 will be considered as rods and at appropriate points these rods terminate in circumferentially grooved ends 16 encircled by coupling 17, the grooves following a screw-thread course permitting the couplings 17 to be secured to the rods by the 110 simple expedient of screwing them thereon.

When the tripvees are installed, a suitable

number of them are disposed on each side of the switch stand and are so situated that one tripvee will trip in one direction and the next tripvee will trip in the opposite direction at the same time, whereby actuating mechanism will engage a tripvee and throw the switch and actuate the next tripvee in order when the actuating means reaches it, thereby returning the first tripvee and setting still another tripvee, if there be more than two in succession, the tripvees moving simultaneously but oppositely in order. Each movement of the tripvee rotates the switch stand and throws the switch points transversely to the line of the track, whereby the main track may be coupled up to the branch track or siding and then restored to the first position while the train is passing, or in case of the siding being coupled up to the main track, the next car or train will straighten out the continuity of the main track, as the case may be.

The tripvees may be arranged in continuous, though successively alternate, series on one side of the main track at such a distance therefrom as to offer no interference with vehicles traveling along the main track or along the siding, and the tripvees may be duplicated wherever desired on opposite sides of the main track with the same freedom from interference.

The arms 14 of the tripvees are elastically mounted so that when one is engaged by an operating device it will yield and the next arm will be engaged by the operating device in either direction.

In order to throw the switch points, they are connected by a bar 18 movable crosswise of the track and provided with catches 19 movable in slots of the bar 18 and engaging the flanges of the switch points, while rock members 20 hinged to the ends of bar 18 have crank extremities 21, engaging one end or the other of a flat spring 22 to depress or release it. The spring 22 has the catches 19 carried thereby and movable therewith through said slots.

The rock members 20 are under the control of a rod 23 connected at one end to the rocker arm 5, and at the other end and also at an intermediate point to cranks 23^a of the rock members 20, the movement of said rod causing the ends of the spring 22 to be depressed or released in alternation, whereby the respective lock catch 19 is operated as the switch stand is turned in one direction or the other by the tripvees. The catches release the switch points first, then the points are thrown, and finally the switch is shifted and relocked in the new position, the parts being appropriately timed in action for the purpose.

When the switch stand is operated, the rocker arm 5 is operated and the points are shifted one way or the other to direct the car

or train onto or from the siding in the usual manner, and in so doing one of the catches 19 is released from locking position and the other one then snaps into locking position, as shown in Figures 3 and 4, wherefore the 70 switch points are always held in safety.

In Figs. 11 and 12, there is a diagrammatic representation of a railway motor 24 capable of running upon the tracks A and B. The motor 24, which may be of any appropriate construction, is provided with a casing 25 containing oppositely-movable rack bars 26 terminating at opposite ends in rods 27 carrying rollers 28 so located that they may engage between the arms 14 of the tripvees on opposite sides of the track. By means of appropriate gearing 29 and a manipulating hand-wheel 30, the rollers 28 may be projected laterally or retracted with reference to the tripvees and thus be under the 85 control of an operator to cause the actuation of the tripvees and the throwing of the switch as the operator desires.

What is claimed is:—

1. Operating means for railroad switch points, comprising a rockable switch stand connected to the points, a tripvee mounted to oscillate on a horizontal axis and connected to the stand, and vehicle-carried means adapted to travel in a path to enter and actuate the tripvees, that portion of the tripvees entered by the vehicle-carried means comprising divergent arms movable independently of each other in the same vertical plane. 100

2. Operating means for railroad switch points, comprising a rockable switch stand connected to the points, a tripvee mounted to oscillate on a horizontal axis and comprising an upwardly-opening V-shaped entering 105 channel formed by arms divergent from each other and pivotally mounted and movable toward each other, connections from the tripvee to the switch points, and means capable of traveling along the railroad and entering and operating the tripvee. 110

3. Operating means for railroad switch points, comprising a rockable switch stand connected to the points, a tripvee mounted to oscillate on a horizontal axis and comprising an upwardly-opening V-shaped entering channel, connections from the tripvee to the switch points, and means capable of traveling along the railroad and entering and operating the tripvee, the tripvee having 115 upwardly-directed divergent arms and spring controlling means for maintaining the arms in divergent condition and yielding to forces tending to cause the approach of the arms. 120

4. Operating means for railroad switch points, comprising a rockable switch stand connected to the points, a tripvee located at one side of the railroad track out of the path of a vehicle on the railroad, a plurality of locks alternately operated and each adjacent 130

a switch point for alternately engaging its respective switch point to hold the switch points in either position of adjustment, and vehicle-carried means for engaging and 5 operating the tripvees in either direction of movement of the vehicle.

5. Operating means for railroad switches, comprising tripping devices with upstanding open mouths or entrances normally inclined 10 to the vertical and each device tipping oppositely to the next in order, said entrances in the trip devices being formed by a pair of divergent members resiliently mounted on the tripping devices.

15 6. Operating means for railroad switches, comprising a series of connected tripping devices mounted to rock in opposite directions and connected in order, said devices having upstanding open mouths normally 20 inclined to the vertical and alternately tipping in opposite directions to each other, the devices comprising divergent arms pivoted at their lower ends and provided with springs normally retaining the arms in the 25 divergent position.

7. Operating means for railroad switches, comprising a switch stand having a rocker arm connected to the switch points, a transverse bar below the switch points, locking 30 devices on the bar for engaging the switch points, a spring for said locking devices, means whereby said locking devices may be actuated by the rocker arm, and tripping devices located at the sides of the track and 35 connected to the rocker arm.

8. Operating means for railroad switches comprising a switch stand having a rocker arm with connections therefrom to the points of the switch, a transverse bar movable be- 40 low the points of the switch and having slots therein, a spring arranged below the bar, catches carried by the spring and operating through the slots of said bar and en- gaging the switch points, rock members at 45 each end of the bar and adapted to engage with the spring, and a rod connecting the rock members to the rocker arm of the switch stand.

9. In operating means for railway 50 switches, connected, shiftable switch points,

a plate underlying the switch points, lock catches yieldable to the shifting of the points and having a normal tendency to rise through the plate into the path of lateral movement of the points, and means for depressing the 55 catches out of the path of the switch points and timed in operation to move the catches in alternation out of the path of one point as both points are shifted, whereby both points are positively locked in one position 60 or the other by one of the catches through the connection between the points.

10. In operating means for railway switches, a switch stand, connections therefrom to the points of the switch, a plate over 65 which the switch points are movable, slots in the plate laterally of the track in which the switch points are located, lock catches projectable through the slots, a spring carrying the catches and having a normal upward 70 trend to lift the catches through the slots into the path of the switch points, and means for alternately depressing the catches in opposition to their normal tendency, with one catch rising through a respective slot while 75 the other catch is forced down through the slot.

11. In operating means for railway switches, a switch stand, connections therefrom to the points of the switch, a plate over 80 which the switch points are movable, slots in the plate laterally of the track in which the switch points are located, lock catches projectable through the slots, a spring carrying the catches and having a normal upward 85 trend to lift the catches through the slots into the path of the switch points, and means for alternately depressing the catches in opposition to their normal tendency, with one catch rising through a respective slot while 90 the other catch is forced below the slot, said last named means comprising crank devices movable into engagement with the spring, and connections from the crank devices to the switch stand. 95

In testimony that I claim the foregoing as my own, I have hereto affixed my signature.

FRANK H. MARTIN.
